UNITED STATES PATENT OFFICE.

HARRY F. VOELKER, OF YORKLYN, DELAWARE.

EXPANSION BOLT.

Application filed February 8, 1922. Serial No. 534,886.

To all whom it may concern:

Be it known that I, HARRY F. VOELKER, a citizen of the United States, residing at Yorklyn, in the county of New Castle and State of Delaware, have invented certain new and useful Improvements in Expansion Bolts, of which the following is a specification.

The invention relates to expansion bolts, and has as an object the provision of such a device which may be placed in a perforation in a structure with readiness, and which may be expanded to effectively grasp the walls of the perforation.

15 A further object of the invention is the provision of a casing which may be placed about an expansion bolt to enable the same to be more readily placed.

An illustrative embodiment of the invention is shown in the accompanying drawings, in which

Fig. 1 is a central longitudinal section, parts being shown in elevation.

20 Fig. 2 is a perspective view, partly broken away, of the casing.

Fig. 3 is a plan view of a blank from which the casing may be produced, and

25 Fig. 4 is a perspective view on a reduced scale and partly broken away of a portion 30 of wall with the casing expanded therein.

A difficulty with the application of expansion bolts heretofore has been that the different parts fall out of their relation to each other while being placed in the opening if the opening chances to have irregular walls.

The present invention provides for a removal of this difficulty by the provision of a casing 10, which is shown as comprising a 40 sheet of material bent into cylindrical form, and provided with a bottom 11. To hold the sheet of material in its position in cylindrical form one edge of the blank 12 from which it is produced is provided with tongues 45 13, and the opposite edge of the blank is provided with slots 14, into which the tongues may be introduced, as clearly shown in Fig. 2.

To retain the bottom 11 of the cylinder 50 one edge of the blank 12 may be crimped to form a flange, as shown at 15, against which the bottom 11 may be laid from the interior.

The expansion device is shown as comprising a plurality of members 16 which, 55 when assembled, produce a complete cylinder, and which are provided with prominent

ridges 17 upon their exterior, which ridges are adapted to bite into the walls of the opening when the member is expanded. To expand the device 16 the interior thereof is 60 threaded but is formed upon the surface of a cone tapering toward its inner end. When the screw threaded bolt 18 is screwed into the expansion device the members 16 will forcibly spread, as shown in Fig. 4, in a 65 well known manner.

To retain the assembled expansion members in the casing during shipment and handling the edge of the casing is crimped and bent into a flange 19 in the same manner as 70 the flange 15 already described is formed. The flange 19 is formed after the assembled members are introduced into the casing and ensures that the expansion device will remain in its position ready for use when in 75 shipping or storing operation.

The construction of the casing 10 is such that it may be readily ruptured by the expansion of the expansion device, allowing the ridges 17 to either pierce its walls or 80 indent them so as to carry the walls of the casing outward into the walls of the perforation in which the bolt is placed.

The casing 10 may be formed of any suitable material, a light gauge tin being at 85 present preferred. When the portions 16 of the expansion device are assembled within the casing 10 they are securely held in such a position that they may be handled as an entity and may be readily introduced into 90 the perforation where it is desired to secure the bolt 10, without losing their relation to each other.

The device is capable of being used in many positions which have been impossible 95 with devices of the prior art. It is even possible to wire them in place upon forms into which concrete has to be poured and to apply the bolt to the device while the concrete is still wet. To provide for entry of the screw 100 18 into the assembled device in proper alignment and to guide the same into engagement with the threads a portion 20 of the expansion device is made without threads and cylindrical of a size sufficient to permit of ready 105 entry of the bolt 18.

If necessary the device may be removed after expansion within an opening since the flexibility of the shield will permit of its squeezing together and pulling out of the 110 opening when the bolt 18 has been unscrewed, so that nearly enough threads are

in engagement to give a hold upon the expansion device to pull it with its shield out of the hole.

The complete enclosure of the expansion device in the shield prevents any material, such as sand or broken stone, getting access to its interior, and thereby interfering with the ready placing of the device.

Minor changes may be made in the physical embodiment of the invention without departing from its spirit.

What I claim as new and desire to secure by Letters Patent is:

1. In an expansion bolt, in combination, a plurality of readily separable members having protuberances upon their outer surfaces, a readily rupturable and deformable casing adapted to hold said members in assembled position, anchoring means adapted to be forced between said members to spread the same whereby to force said protuberances

into contact with the walls of an opening in which it is desired to secure said anchoring means with deformation of the walls of the casing.

2. An expansion bolt, comprising, in combination, a plurality of separable members having a tapered threaded opening formed therebetween when in assembled position, a bolt adapted to be screwed into said opening to spread the members, protuberances upon the outer surfaces of said members, a casing of material adapted to be deformed by said protuberances when said members are expanded and having the edges of the blank from which it is formed loosely secured together enclosing said members, a bottom in said casing, a flange upon the mouth of said casing overlapping said members to prevent their removal therefrom.

HARRY F. VOELKER
